STEERING GEAR

Albert J. Dawson, Sewickley, Pa.

Continuation of application Serial No. 97,022,
August 20, 1936. This application January 14,
1938, Serial No. 185,032

2 Claims. (Cl. 60—52)

This application is a continuation of application Serial No. 97,022, filed August 20, 1936, on Steering gear.

My invention relates to the steering of ships, and consists in refinements in apparatus for powerfully swinging the rudders.

Ship-steering apparatus has been built and used hitherto in which, associated with a hydraulic ram, a reservoir of ram-operating liquid is provided, and, associated with the reservoir, a motor-driven pump. The pump and its motor operate continuously, and liquid supplied by the reservoir is circulated between the outlet and inlet of the pump. In this line of liquid circulation a valve-chest is arranged, and in such chest a valve, responsive to the helm of the ship, is movable to either side of a neutral position. In the neutral position of the valve the line of liquid circulation is open, and communication between the opposite ends of the ram and the pump is cut off. When the valve is shifted to one side of the neutral position or the other, the pump delivers liquid under pressure to one end of the ram or the other, and removes liquid from the opposite end; the plunger of the ram is shifted (one way or the other according as the valve is shifted), and the rudder of the ship is powerfully turned to the port or the starboard, depending upon which way the ram moves.

In the operation of such known apparatus it has been found that the rudders are not delicately responsive to the helm. When the valve is shifted from neutral position there is a momentary wait before the pump builds up adequate operating pressure in the liquid delivered to the ram, and during such interval of lag the rudder, subject to stress, tends to turn in retrograde direction.

The object of my invention is to provide ship-steering apparatus which is more minutely responsive to the helm, and in which such retrograde motion of the rudder is substantially eliminated. The invention consists in refinement and elaboration of apparatus of the sort described above.

In the accompanying drawings Fig. I is a diagrammatic view in plan and section of the steering apparatus of a dredge boat in which the invention has been embodied; Fig. II is a view to larger scale, showing in axial section the control valve which, responsive to the will of the pilot, renders the apparatus effective; and Fig. III is a fragmentary view, to larger scale than Fig. I, affording fuller illustration of certain parts.

Referring to Fig. I, two pairs of rudder-posts

1, 1, 2, 2, equipped with tillers 3, 3, 4, 4, may be understood to be carried by a single boat, and to be rotated, pair by pair, in unison to effect steering.

For the two pairs of tillers two steering rams 5, 6 are provided, one for each pair, and the assembly is such that as the piston of the steering ram is shifted the tillers associated with it are swung. The rams are hydraulic.

Referring to Fig. III, a rotary screw pump 1, 10 constantly driven by a motor 8, constantly circulates a ram-operating liquid (ordinarily oil) through a circulation system, from exit 9 to intake 10. In the circulation system a valve-chest 11 is included; from the valve-chest connections 12 and 13 extend to the ends of the cylinder of the ram 5; and within the valve-chest a valve 14 is arranged. The valve-chest is a cylinder with ported walls, the valve consists of a set of discs mounted at properly spaced intervals upon a common stem, and the valve structure is movable longitudinally within the cylinder in response to the will of the pilot. In Fig. III the valve is shown in neutral position, and it will be perceived that the pump is effective to circulate liquid through the system, in a line of flow indicated by arrows. When the valve 14 is in this neutral position there is no hydraulic connection to cylinder 5. It will further be perceived that, if the valve 14 be shifted in either direction from the position of Fig. III, a line of flow will be opened through a branch 15 and valve-chest 11 to one of the connections 12 and 13, while the other connection (13 or 12) will be brought into outflow communication through valve-chest 11 with a branch 16. And at the same time the direct line of circulation through the valve-chest (that indicated by arrows in Fig. III) will be cut off.

More specifically, if the valve 14 be shifted 40 in upward direction, as viewed in Fig. III, disc *d* of the valve, rising, will close a lead *a* and cut off the line of direct communication between discharge line 9 and return line 16; disc *f* will open a line of communication from branch 15 to lead 45 12 of the ram; and disc *g* will open a line of communication from lead 13 of the ram to a lead *c* opening into return line 16. If the valve 14 be shifted in downward direction, the disc *e* of the valve will cut off communication between 50 discharge line 9 and the lead *a* of return line 16; the line of flow from the pump will be opened from lead 15 to lead 13, while the lead 12 will be brought into communication with a lead *b* opening into return line 16. Thus, while one end of 55

the ram is subjected to the driving power of the pump, the opposite end is opened for return flow of the liquid to the pump intake. In consequence of such shifting of the valve, the ram 5 operates and swings the tillers 3, 3 in one direction or the other.

The ends of the valve-chest 11, beyond the range of valve reciprocation, are brought into communication, by means of a pipe connection 10 17; the connections 17 of the two ram assemblies (Fig. I) are interconnected by a line 170 that communicates through a lead 171 with a sump-tank 18 including a supply of the ram-operating liquid. The liquid-circulating system of each 15 ram assembly may drain into the sump-tank, and, by the action of the pumps, the system may be filled with liquid from the tank. The pipe connection 17 provides escape for the gas or oil which, collecting and standing in the ends of the 20 valve-chest, would otherwise oppose the shifting of the valves.

Fig. II is a working drawing of the valve-chest structure; to it reference numerals and arrows have been added, and these, taken with the 25 diagrammatic showing of Fig. III, will make structure and operation plain.

The apparatus of the invention is provided with a line 19 of communication from the main line of liquid circulation, at a point between the 30 outlet of the pump 7 and the valve-chest 11, to the tank 18; in this line of communication a pressure relief valve 22 and an air chamber 20 are included, and the relief valve, normally standing in closed position, opens only when a 35 pressure of critical value (say 350 pounds) is attained.

A second and smaller screw pump 23, also 40 constantly driven by motor 8, is in constantly open communication with the supply tank 18. Pump 23 delivers a stream of liquid to a pipe 24, whence there is a double line of flow. One line is a line 45 25 of return flow to the intake side of the pump 23, and the other line is a line of delivery to the circulating stream that pump 7 impels from outlet 9 to inlet 10, and on the delivery side of the valve-chest 11. In the line 25 of return flow is a relief valve 27 that opens only when a critical 50 pressure of less value than the critical pressure of relief valve 22 is attained—in this case a pressure of 200 pounds. Under the influence of pump 23 the body of liquid that idly circulates, when the valve 14 is in the position shown in Fig. III, is maintained under a pressure equal to the critical 55 value (200 pounds) fixed by the valve 27. The relief valve 22, only opening at a critical pressure of 350 pounds, remains closed while the liquid is in this manner idly circulated.

At all times, except when the pressure of the 60 circulating stream of pump 7 falls below 200 pounds (such as occurs when the valve 14 is in course of being shifted) the relief valve 27 stands in open position and the pump 23 is effective to circulate oil through return line 25. The pressure that then is effective in circulating the oil 65 through return line 25 equals the margin by which the pressure generated by pump 23 exceeds said critical pressure of valve 27. It will be understood, therefore, that when valve 14 is shifted and the direct line of communication between the outlet lead 9 of pump 7 and the return lead 16 is blanked (as already described) a pressure of substantially 200 pounds is immediately effective upon that end of the ram to which lead 15 opens. Simultaneously, communication is 70 opened from the opposite end of the ram, through 75

branch 16, to the inlet of the pump 7. And, while it is true that lead 26 opens to the return branch 16, the capacity of the pump 23 is so much lower than the capacity of pump 7 and the rate of discharge of pump 23 is so far below the rate of intake of pump 7, that the 200-pound pressure normally prevailing in branch 16 is immediately dissipated. Thus the pressure constantly maintained by pump 23 becomes effective when valve 14 is shifted to hold the ram from retrograde 10 movement. There is no momentary relief or wait until the pump 7 builds up the pressure of the liquid to ram-operating value—an effective pressure differential between the opposite sides of the ram is instantly obtained and held 15 throughout the range of operation. Thus it is that the rudder, which might otherwise respond to retrograde turning stress when the valve 14 is in course of being shifted, is positively held in position, ready when the shifting of valve 14 20 is completed to respond to the steering apparatus. Retrograde turning is resisted and prevented.

Assuming for purposes of explanation that pump 23 and its connections are eliminated, when the valve 14 is shifted from the inactive or 25 neutral position shown in Fig. III of the drawings to a position in which the pump delivers to cylinder 5 at one end and cylinder 5 at the opposite end delivers to the intake of the pump 7, then the power of the pump 7 is exerted to shift the 30 piston within cylinder 5, and to retain it at the limit of its traverse. When that limit has been reached, the oil ceases to circulate, and under the influence of the pump 7 the pressure of the liquid between the outlet of the pump and the 35 power end of the ram immediately rises above the normal value of 200 pounds set by relief valve 27. The pressure rises until the critical pressure (350 pounds) of relief valve 22 is reached, whereupon such relief valve opens and the liquid delivered by pump 7 flows through pipes 19, 17, and 171 into the tank 18. While the relief valve 22 is open, however, the pressure of the liquid in the power end of the ram remains at 350 pounds, operating powerfully to maintain the parts in the 40 45 positions to which they have come.

The two relief valves 22 and 27, with the pumps 7 and 23 and their connections, have the effect of maintaining the stream of oil that circulates, while the valve 14 is in neutral position, at a pre-determined pressure of 200 pounds. This pressure of 200 pounds is like a spring, effective, when the valve 14 is in course of shifting, to prevent retrograde turning of the rudder, and it is in virtue of the fact that the power exerted by pump 7 exceeds that exerted by pump 23 that, when the valve 14 has come to the limit of its shift on either side of neutral position, the pump 7 has capacity immediately to increase the effective pressure of the liquid to a value above the normal value of 200 pounds; that is, to a value upward to but not in excess of a maximum value of 350 pounds (the critical pressure at which the relief valve 22 opens), whereby the ram is instantly responsive to the shift of the valve 14.

In the steering of a boat the valve 14 is shifted, held for a greater or less interval of time, and returned to neutral position. According to the length of time that the valve is retained in shifted- 70 aside position, the rudders are swung more widely to left or right, and the direction of swing is in accord with the direction in which valve 14 is shifted. From swung-aside position the rudders may be returned to neutral—that is to say, fore- 75

and-aft—position by the opposite shifting of valve 14.

The pump 23 serves, in addition to the functions already described, to feed oil from the tank 18 to the branch 16, in such quantities as to make up for the return flow to the tank 18 while the relief valve 22 is open and for losses due to leakage in the system.

When the system is to be drained, the normally closed valve 21 is opened and communication established between branch 16 and the tank 18, and pet-cocks 30, arranged in usual way in the system, are opened to the outer atmosphere. The oil drains from the system into the tank 18.

Again, when the system is to be filled, the valve 21 and pet-cocks 30 being open, the pumps 1 and 23 are set in operation. While the pumps are charging in oil from the tank 18, the valve 14 is shifted first to one end of its range of movement and then to the other, thus reciprocating the ram and insuring that all parts of the system are fully charged. Then the valve 21 and pet-cocks are closed and the apparatus is ready for service.

Oil filters or strainers 28 are included at convenient and suitable points in the pipe connections of the system.

I claim as my invention:

1. Steering apparatus including a rudder, a steering ram, a valve-chest, leads for ram-operating liquid between the valve-chest and the opposite ends of the ram, a reservoir of liquid, a line of liquid circulation including said valve-chest, a continuously operating high-capacity pump in said line of circulation, a line of communication between said line of circulation (at a point between said valve-chest and the outlet of the pump) and said reservoir, a high-pressure relief valve in said line of communication, means for imposing augmented pressure, of less value than the critical pressure of said high-pressure relief

valve, on the liquid in said line of circulation, said means including a low-capacity pump adapted to deliver liquid into said line of circulation at a point between said valve-chest and the inlet of said high-capacity pump, a line of return flow between the delivery and intake sides of said low-capacity pump, a low-pressure relief valve in said line of return flow, and a valve in said valve-chest movable between a position in which said line of liquid circulation is open and communication between the pumps and the opposite ends of the ram is cut off, and a position in which said line of circulation is interrupted and communication between the high-capacity pump and the leads to the ends of the ram is established.

2. Steering apparatus including a rudder, a steering ram, a valve-chest, leads for ram-operating liquid between the valve-chest and the opposite ends of the ram, a reservoir of liquid, a line of liquid circulation including said valve-chest, a continuously operating main pump in said line of circulation, a high-pressure relief valve connected to the line of delivery of said main pump, means for imposing augmented pressure, of less value than the critical pressure of said high-pressure relief valve, on the liquid in said line of circulation, said means including an auxiliary pump adapted to deliver liquid into said line of circulation at a point between said valve-chest and the inlet of said main pump and a low-pressure relief valve on the delivery side of said auxiliary pump, and a valve in said valve-chest movable between a position in which said line of liquid circulation is open and communication between the pumps and the opposite ends of the ram is cut off, and a position in which said line of circulation is interrupted and communication is established between the main pump and the leads to the ends of the ram.

ALBERT J. DAWSON.
